UNITED STATES PATENT OFFICE

CARL F. ADAM, OF TRENTON, NEW JERSEY

INHALER

Application filed March 16, 1925. Serial No. 15,949.

This invention relates to inhalers, and more particularly to inhalers adapted for the generation or storage of such substances as chlorine for the treatment of colds, etc., and includes the novel inhaler structures set forth below, together with the processes and compositions herein set forth.

The recent development in the treatment of colds and related ailments by chlorine has created the need for a simple pocket inhaler which although it may be carried around by any one without gradual loss of its chlorine content, is available for use when desired. Such inhalers supply obvious advantages over the preparations now on the market and usually manufactured in tablet or liquid form, which must be mixed with water, etc., in order to generate the chlorine, etc.

One of the objects of this invention is to supply a convenient chlorine inhaler which permits of the storing of the chlorine for indefinite periods.

Another object of this invention is to provide compositions which will generate chlorine gradually, particularly desirable in such chlorine inhalers.

A further object of this invention is to supply inhalers for the storing and generation of chlorine which may be simple in construction, cheap to manufacture, and easily carried in a pocket for example.

Other and further objects and advantages will appear from the more detailed description set forth below, particularly taken in connection with the accompanying drawings wherein there is shown by way of illustration:

In Figure 1, one form of a completed inhaler;

In Figure 2, a section through the inhaler of Figure 1;

In Figures 3 and 4 fragmentary sections on lines 3-3 and 4-4 of Figure 2;

In Figure 5, a modified form of the inhaler shown in section;

In Figure 6, one form of the inner vial having one end permanently closed;

In Figures 7 and 8 modified forms of the outer vial;

In Figures 9 and 10 modified forms of the inner vial; and

In Figure 11 a further modification of the complete inhaler structure shown in section.

In Figure 12, a sectional view of a further modification of the inner vial, as filled and ready for assembly.

It will now be apparent that this inhaler comprises a structure in which there is an inner vial for containing the desired chlorine storing or storing and generating composition, an outer vial surrounding the first named vial with means for retaining the inner vial in a more or less fixed position within the outer vial, and preferably in spaced relation so that there is maintained between the outer and inner vials, a space preferably closed to the entry of chlorine gas, so that advertising matter may be placed within this space between the vials, and any printing or printed matter on the advertising circular will thus not be subjected to the destroying action of the chlorine fumes.

Turning to the more specific forms of this invention showing the inhaler structure, there is found in Figures 1 to 4 an inner vial for containing the chlorine containing composition or mixture, this vial 1 being in this instance a glass tube open at both ends. This inner tube or vial 1 is positioned within the outer vial 2 by means of holding means such as corks 3 and 4 fitting snugly within the outer vial 2, and forced into close contact with the tube 1, so that the latter is relatively fixed in position. This arrangement of the vials forms a space 5 between them in which display advertising etc. may be shown, and such display matter will obviously be cut off from any contact with the chlorine gas or fumes. The corks 3 and 4 as shown in Figures 1 to 4 are preferably perforated or drilled to form a small passageway or opening 6 and 7 in them through which air or air with chlorine may be drawn. When so perforated there is also preferably placed over the corks, a small disc of paper, etc., 8' and 8'', to tentatively close the openings 6 and 7 in the corks, and such discs may carry wording such as "Punch here" as illustrated in Figure 3. The outer vial 2 is also prefer-

ably tapered at one end as shown at 8, for convenience in placing the end of the outer vial within a nostril, and such taper also forms a convenient shoulder against which 5 the holding means 4 and disc 8" may abut. There is also preferably provided in the complete inhaler two stoppers or corks 10 and 11, the first named closing the reduced opening in the tapered end of the inhaler, while the 10 latter closes the opposite opening through which air enters the inner vial or tube.

In the modification shown in Figures 5 and 6, an inner vial 20 is used which is closed at one end as shown at 21. The opposite open 15 end 22 is tentatively closed by a small preferably cork stopper 23, and if desired a celluloid or equivalent coating 24 may be placed over the end 22 of the inner vial 20 to seal the same effectively but tentatively. The 20 inner vial 20 is maintained within the outer vial 2 by a holding means or cork 4 closed by a disc 8" all as set forth under the description of the similar features of figure 1 above. The stopper 3' at the further end of the tube 25 2 maintains the inner vial 20 in position.

In the modifications set forth in Figures 7 to 10 several forms of inner and outer vials are shown with both open ends (Figures 8 and 10) and with one end permanently 30 closed (Figures 7 and 9). The closure of these vials is preferably as follows: The vial is threaded or similarly endowed as shown at 30 and 31 so that a preferably metallic screw cap 32 or 34 may be used to form the 35 outer closure. The usual stopper or cork 35 or 36 is placed in the end of the vial 101 or 102, and when this cork is perforated as shown in the drawings it is preferable to place over the perforated cork, a disc of 40 waxed paper etc. 37 or 38 which may close the perforations in the stoppers tentatively. In one modification of the screw cap as shown at 33, there is an opening or perforation 39 through which the disc 38 for example may 45 be punctured without removal of the screw cap. Such perforated caps while shown as used on the inner vials may be used also on the outer vials if desired.

In the complete vial shown in Figure 11, 50 use is made of some of these modifications to form a very desirable type of inhaler. The outer vial 101 permanently closed at one end 140, is provided with a screw cap 141 adapted to screw over the preferably threaded end 55 30 of the vial 101. This cap 141 is formed with a cylindrical extension 142 open at its outer end 143, and adapted to receive the cap 144 for the purpose of sealing the entire inhaler. The inner vial 20 which may be similar to the form shown in Figure 6 but preferably without the coating 24, is held in place 60 within the outer vial 101 by means of a cushioning member or cork 150 at the closed end, and by means of stoppers 35 and 36 as 65 illustrated. The cap 141 serves to force the

stoppers 35 and 36 down into place so that the inner vial 20 is held against the cushion 150.

In the several modifications set forth above, it has been found convenient to use corks or 70 stoppers which contain a central opening or perforation, and to close this opening tentatively by a washer or disc of paraffined blotter material, paper, rubber, etc. The washer or disc is easily punctured when it is desired 75 to use the inhaler. But it is obvious that in place of this arrangement, a thin disc of cork, paper, etc. might be used which is not perforated, but which may be easily punctured when desired. Further such discs or washers 80 may be placed within the screw cap after a former disc or washer or stopper has been perforated, when it is desired to seal the inhaler against loss of chlorine when not in use.

The chlorine composition may take various forms of which the following may be considered as exemplary. For example when chlorine is used with the inner vial in the form of a tube, a small amount of absorbent 90 material such as cotton is used to plug up one end of the tube. Silica gel or analogous material which has been previously saturated with, and has absorbed dry chlorine is then placed in this tube and the other end is then 95 plugged up with cotton. This filled or charged vial is then inserted into the outer vial. It is thus obvious that the drawing of air into the inhaler after piercing of tentative closures or seals will cause fumes of chlorine to be drawn upward through the inhaler into the nostril. Then when chlorine is generated by means of the reaction of hydrochloric acid upon manganese dioxide, an inner vial with one end permanently closed, is 100 charged with the materials in the following manner: A gelatine capsule previously filled with manganese dioxide is dropped into the acid solution in a vial. Cotton for example, is then placed over the acid, and the entire 105 vial or cartridge closed with a cork stopper which may or may not be of the perforated type set forth above. If desired, this may be 110 further secured in place by one of the screw caps also explained at length above. Since it 115 takes about one quarter of an hour for the acid to digest the capsule, the operator has ample time to fill the vial, and assemble the inhaler if desired, before there is any actual 120 generation of chlorine and pressure developed which pressure later, when it is desired to release the chlorine for inhaling, will expel it and without requiring the air current as described in the silica gel and analogous material, and the method of using such materials.

It is further obvious that any desired chlorine charged composition may be used, or chlorine may be stored and absorbed in an 125 absorbent material which yields chlorine 130

back when a gentle current of air is drawn through the inhaler. Such chlorine carrying material having been used to fill the inner open tube or cartridge may be used in place of the hydrochloric acid-manganese dioxide compositions set forth above in the closed vial construction.

The manner of assembling these inhalers will be obvious from the descriptions set forth above in connection with the various modifications of the inhalers. But the following additional matter appears to be desirable in this connection and particularly in connection with the use of the inhalers. A tube or cartridge or inner vial having been filled in the manner set forth above, or in some analogous manner, the cartridge or vial is inserted into the outer vial abutting against a cork or other stopper 4 or 30 as the case may be. Or in the case of the modification shown in Figure 11, the vial is placed with its inner end abutting the cushioning member 150. A stopper or cork 3 may then be inserted against the other end of the vial or cartridge to hold it in place. Discs such as 6 and 7 are used whenever desirable as set forth above. In the case of the device as shown in Figures 2 and 5, the stopper or cork 10 is then inserted to close the device. When it is desired 30 to use the inhaler, stoppers 10 and 11 are removed, and the corks 3 and 4 punched at the points indicated. By then applying the tapered end of the inhaler to the nostril, and inhaling, a sufficient gradual flow of chlorine impregnated air is obtained.

In the modifications shown in Figures 7 to 11, the outer screw caps together with discs are used to seal the inhalers, the punching taking place after removal of the outer screw cap. When perforated screw caps such as those shown in Figures 9 and 10 are used on the outer vials, the punching may take place without removing the screw caps. Subsequently if it is desired to tentatively seal the inhaler after punching, new discs may be inserted under the screw caps.

In the modification shown in Figure 11, the cartridge having been placed within the outer vial and abutting against the cushioning cork 150, the stopper 35 is inserted so that its opening is aligned with that in the stopper 36. A disc having been inserted within the screw cap 141, this cap is screwed into position and serves to maintain the parts in fixed position against movement. The outer screw cap 144 is then screwed on. To use this form of inhaler, the outer cap 144 is removed, and the stoppers punched straight through so that the opening into the inner vial or cartridge is made.

An inner vial having a perforated screw cap may also be used in this modification and when brought slightly above the outer vial, will be held tightly in fixed position by the outer screw cap 141, previously suitably

washed. This form of the inhaler may be sealed tentatively by replacing the outer cap 144.

In the modification shown in Figure 12, an inner vial 102 is used which is permanently closed at one end in the preferred form. At the open end the vial is provided with a screw cap 33, a disc 38, and the screw cap is also preferably provided with the opening 39, tentatively closed by the disc 38, all as more specifically set forth above. A capsule 42 containing manganese dioxide, or other selected material, is placed at the closed end of the vial, and over this is placed a saddle member 41. The saddle member or separator may take any desired form, one such form being illustrated, its principal function being to prevent the absorbent cotton or etc. 43 from being pushed too far into the tube. The use of a saddle also enables the operator to assemble such inhalers more rapidly.

While the procedure set forth above may be used, it has been found to be preferable to fill the inhaler as shown in Figure 12 as follows. The acid is first placed in the inner vial 102, after which the capsule containing the manganese dioxide is dropped into the acid. Cotton and cork follow in the same manner as set forth above. This procedure is desired since the acid may be allowed to stand in the vials for a length of time.

In place of using a perforated cork for the stopper as set forth above, together with a separate disc of material to close the perforation, a label showing the words "Punch here" may be pasted on the cork over the perforation. Or when desired, a thin disc of cork unperforated may be used, which is adapted to be easily punctured.

While this invention has been described above as particularly useful in the generation of chlorine, it will be obvious to those skilled in the art that the same principles may be applied in using such structures for the generation of other gases or vapors.

Having thus set forth my invention, I claim:

1. In an inhaler, a vial containing hydrochloric acid and a capsule of manganese dioxide, the capsule being in contact with the hydrochloric acid.

2. An article of manufacture comprising a vial containing a capsule of manganese dioxide, the capsule being in contact with hydrochloric acid contained in the vial, there being absorbent material in said vial.

3. As an article of manufacture, a vial permanently closed at one end containing hydrochloric acid near the closed end of the vial, a capsule containing manganese dioxide in contact with the hydrochloric acid, absorbent material between the acid and the open end of the vial, and a closure for the vial.

4. An inhaler comprising an outer vial permanently closed at one end, an inner vial per-

manently closed at one end containing a chlorine generating composition, the inner vial being maintained in spaced relation to and within the outer vial, perforated stoppers in each of the vials, the stoppers being adjacent to each other with their perforations in alignment, and means for tentatively closing the perforations.

5. An inhaler comprising an outer vial permanently closed at one end, an inner vial permanently closed at one end containing a chlorine generating composition, the inner vial being maintained in spaced relation to and within the outer vial, perforated stoppers in each of the vials, the stoppers being adjacent to each other with their perforations in alignment, means for tentatively closing the perforations, and screw caps on the inner and outer vials.

23 6. In an inhaler, a vial containing a capsule of manganese dioxide, a saddle separating the capsule from absorbing material contained in the vial, and hydrochloric acid in contact with the manganese dioxide.

23 7. In an inhaler, a vial closed at one end, containing a capsule of manganese dioxide immersed in hydrochloric acid, a saddle member surrounding the capsule, but allowing access of the acid to the capsule, absorbing material above the capsule and acid, extending to the open end of the vial, and a stopper on said vial.
